UNITED STATES PATENT OFFICE.

WILLIAM C. LAWSON, OF RURAL RETREAT, VIRGINIA.

AERIAL TRAMWAY.

No. 826,340.

Specification of Letters Patent.

Patented July 17, 1906.

Application filed January 23, 1906. Serial No. 297,618.

To all whom it may concern:

Be it known that I, WILLIAM C. LAWSON, a citizen of the United States, residing at Rural Retreat, in the county of Wythe and State of Virginia, have invented a new and useful Aerial Tramway, of which the following is a specification.

This invention relates to aerial tramways, and more particularly those employing cables on which the carrying devices run and by which they are supported. The ordinary tramway of this character now in general use employs a single supporting-cable which has a number of objections, among which may be mentioned the cost of a single large cable, the power necessary to move the carriers along the same and up the inclined portion caused by the necessary sag of such cable, the liability of the cars to sway, and the excessive wear due to such swaying movements. It has been proposed to employ two-rail cable structures; but so far as I am aware these have been proven impracticable, as it has been very difficult to obtain an equal tension on both rails or cables, and without such tension unequal strains, the shifting of the loads, and the displacement of the carriers are almost necessary consequences.

The principal object of the present invention is to provide a novel and simple structure whereby a plurality of cable-rails may be employed and equal tension on both can be readily secured and maintained, thereby obviating the objections above set forth.

Another object is to provide effective means for securing the parts in place, so that there is little liability of derangement.

A still further object is to provide a sectional structure which is much less expensive than the ordinary type, is capable of sustaining great loads, can be provided with curves as required under different conditions of use, can be made stronger at necessary points without the necessity of correspondingly increasing the strength of the entire structure, and can be readily and cheaply constructed and installed.

The preferred embodiment of the invention is illustrated in the accompanying drawings, wherein—

Figure 1 is a perspective view of a portion of the structure. Fig. 2 is a vertical longitu-

dinal sectional view, on an enlarged scale, through the same. Fig. 3 is a top plan view of one of the supports and the associated parts. Fig. 4 is a cross-sectional view on the line 4 4 of Fig. 3. Fig. 5 is a cross-sectional view on the line 5 5 of Fig. 2. Fig. 6 is a detail perspective view of one of the cable-holding devices. Fig. 7 is a vertical longitudinal sectional view therethrough. Fig. 8 is a horizontal sectional view on the line 8 8 of Fig. 7. Fig. 9 is a vertical sectional view on the line 9 9 of Fig. 7. Fig. 10 is a top plan view showing the manner in which curves are made. Fig. 11 is a side elevation of the same.

Like numerals of reference designate corresponding parts in all the figures of the drawings.

In the embodiment illustrated spaced supports are provided comprising suitable spaced standards 12, to the upper ends of which are fastened spaced cross-beams 13. Mounted transversely on these cross-beams are sets of spaced angle-plates 14, to and between which are journaled guide-sheaves 15. On every other support are also mounted other guide-sheaves 16, which sheaves are disposed between the cross-beams longitudinally thereof and journaled thereto. In the present embodiment a double track is illustrated, and each track is composed of independent sections, a section extending from one support to the next. As these sections are similar in all respects, a description of one is believed to be sufficient for all. Each track-section is composed of a single looped cable, the looped end portion 17 of such cable passing over a set of the guide-sheaves 15 and about the intermediate sheave 16. Its ends 18 pass over the corresponding sheaves 15 of the next support and downwardly through holding-blocks 19, being secured by clips 20, fastened to said ends below the blocks, as shown in Fig. 5. As a result the side portions 21 of said single looped cable form spaced carriage-supporting rails, and by the term "carriage" it is intended to embrace any carrying or transporting device capable of operating on the rails.

It will be observed by reference to Figs. 6 and 7 that the guide-sheaves 15, mounted in each set of plates 14, are slightly spaced apart, and consequently the corresponding ends of

the track-sections will also be spaced slightly apart. These spaces are bridged, however, by clamping-plates 22, constituting, in effect, track-sections, which plates have their upper ends extending outwardly and their edges serrated, as shown at 23, to clamp against the portions of the cables passing over the sheaves 15. These clamping-plates extend downwardly between the angle-plates 14, which plates 14 have slots or openings 24. Engaged in said slots or openings are clips 25, embracing the cables and normally holding the same against movement. These clips furthermore engage in seats or sockets 26, formed in the opposite side edges of the clamping-plates 22, and thus serve to hold said clamping-plates in position.

The traction-cable is shown at 27, and it is located between and slightly below the plane 20 of the cable-rails 21. This traction-cable passes over the supports between the guide-sheaves and angle-plates 14 and is supported in any suitable manner—as, for instance, by guide-rollers 28—journaled in brackets 29, 25 which brackets are fastened to the sides of the supports. In the present embodiment suitable carriages or carrying devices 30 are shown in Fig. 1, said devices having clutches 31, that engage the traction-cable, and having rollers 32, that run upon the track-rails 21. As the rollers 32 are located on the outer sides and preferably contiguous to the tops of the carrying devices or carriages, it will be seen that said devices are located between the 35 rails.

It will be apparent that this structure can be readily manufactured and cheaply installed. Inasmuch as each section is separate from the other, the carrying capacity of the 40 tramway is equal not to the capacity of a single span, but depends upon the number of sections employed. Furthermore, if some of the sections have to be made longer than others in crossing gorges or the like the cables for that particular section may be made 45 heavier without affecting and altering the other sections, and thus without increasing the cost, except for the particular section in question. Another great advantage is that 50 in this invention the two cable-rails 21 of each section can be placed under equal tension, for, as already shown, each section is a single cable disposed in the form of a loop. Therefore by loosening the various clips securing the looped section and placing tightening strain upon the ends or end by any suitable mechanism the tension of necessity 55 must be equal upon both of the rails formed by said cable, and when the clips are retightened this tension will be maintained. Moreover, should any one cable become broken or 60 injured that cable can be removed and replaced by a new one without the necessity of an entirely new structure, and by making the

tramway in short sections comparatively 65 light and therefore much more inexpensive cables may be employed.

In case it is desired to provide a curve in the tramway the structure disclosed in Figs. 10 and 11 is employed. The track-sections 70 composed of the looped cables are the same as already described and have therefore been given the same reference-numerals. These sections are, however, spaced apart and disposed in angular relation, as shown in 75 Fig. 10, and interposed between them are curved track-plates 33, the outer ends of which are located between the angle-plates 14 of the cable-mountings and are secured thereto not only by the clips 24, but also preferably by additional bolts 25. In case the curve is a long one the plates 33 may be in sections, as shown, their ends being coupled together, as shown at 34, and mounted on an intermediate support 35, the arrangement of 80 course depending upon the character of the turn to be made. The traction-cable 27 is passed over suitable guide-sheaves 36, which are set at the proper angle to prevent the cable from riding off the same. It will be observed that this structure corresponds in all 85 essential details to the arrangement already described, the curve plates 33 constituting, in effect, the clamping-plates between the cable-sections, performing an additional 90 function in that by means of them curves in the tramway may be readily effected.

From the foregoing it is thought that the construction, operation, and many advantages of the herein-described invention will 95 be apparent to those skilled in the art without further description, and it will be understood that various changes in the size, shape, proportion, and minor details of construction may be resorted to without departing from the spirit or sacrificing any of the advantages 100 of the invention.

Having thus fully described my invention, what I claim as new, and desire to secure by Letters Patent, is—

1. In an aerial tramway, a track including a plurality of carriage-supporting rails formed from a single cable, and means for maintaining the rails in taut condition and against longitudinal movement.
2. In an aerial tramway, a track including a plurality of carriage-supporting rails formed from a looped cable, the sides of said loop constituting said rails, and means for clamping the rails against longitudinal movement.
3. In an aerial tramway, the combination with a support, of guides mounted on the support, and a looped cable having one end portion passing about the guides, the sides of said loop being spaced apart and constituting carriage-supporting rails.
4. In an aerial tramway, the combination

with a support, of spaced guide-sheaves mounted on the support, another guide-sheave mounted on the support between the spaced sheaves and transversely thereof, and 5 a looped cable having its looped end portion passing about the sheaves, the sides of said looped cable being spaced apart and constituting carriage-supporting rails.

5. In an aerial tramway, the combination o with spaced standards, of spaced cross-beams connecting the same, spaced sheaves mounted transversely of the cross-beams, another sheave mounted between the beams longitudinally thereof and between the spaced 5 sheaves, and a looped cable having its looped end portion passing about the spaced sheaves and the intermediate sheave, the sides of said loop being spaced apart and constituting carriage-supporting rails.

6. In an aerial tramway, the combination with spaced supports, of a looped cable having its side portions stretched between the supports and forming spaced carriage-supporting rails, the looped end of the cable being movably guided on one of the supports, and means mounted on the other support for securing the ends of the cable.

7. In an aerial tramway, the combination with spaced supports, of a looped cable having its side portions stretched between the supports and forming spaced carriage-supporting rails, sheaves mounted on one of the supports for guiding the looped end portion of the cable, and clamps mounted on the other support for securing the ends of the cable.

8. In an aerial tramway, the combination with a support, of a guide mounted thereon, a rail-cable passing about the guide, a clamp engaging the cable, and a holding device ent-40 gaging the cable and also engaging the clamp to hold the same in position.

9. In an aerial tramway, the combination with a support, of a guide-roller mounted thereon, a rail-cable passing about the roller, 45 a clamp engaging the portion of the cable that passes about the roller, and a holding-clip embracing the cable and also engaging the clamp to hold the same in position.

10. In an aerial tramway, the combination 5c with supporting-standards, of cross-beams mounted thereon, spaced plates located on the beams, a roller journaled between the plates, a rail-cable passing over the roller, a clamp-plate interposed between the spaced 55 plates and engaging the portion of the cable that passes over the roller, said clamp-plate having a recess, and a holding-clip embracing the cable and engaging in the recess of the clamp-plate.

11. In an aerial tramway, a track composed of a series of sections, each section comprising a plurality of spaced carriage-supporting rails formed from a single cable.

12. In an aerial tramway, a track com-65 posed of a series of sections, each section

comprising a looped cable independent of the other section, and each looped cable forming spaced carriage-supporting rails.

13. In an aerial tramway, the combination with a plurality of spaced supports, of guides mounted on the supports, and a track composed of a series of sections, each section extending between a set of supports and comprising a looped cable extending about the guides on one of the supports and having its 70 ends affixed to the other support.

14. In an aerial tramway, the combination with a plurality of spaced supports, of spaced guide-sheaves mounted on each support, a plurality of looped cables, each cable having 80 its ends secured to one support and having its looped end portion passing over the sheaves of the other support and extending across the space between said sheaves.

15. In an aerial tramway, the combination 85 with a plurality of spaced supports, of spaced guide-sheaves mounted on each support, a plurality of looped cables, each cable having its ends secured to one support and having its looped end portion passing over the 90 sheaves of the other support and extending across the space between said sheaves, and track-section plates bridging the spaces between the ends of the adjacent cables.

16. In an aerial tramway, the combination 95 with a plurality of cable-track sections disposed in angular relation and having their ends spaced apart, of a curved track-plate interposed between and having its ends alined with the adjacent ends of the sections.

17. In an aerial tramway, the combination with a plurality of cable-track sections disposed in angular relation and having their ends spaced apart, of a curved track-plate interposed between and having its ends alined 100 with the adjacent ends of the sections, said track-plate constituting clamps therebetween that engage the sections.

18. In an aerial tramway, the combination with supporting means, of guides mounted thereon, angularly-disposed track-cables passing over the guides, and a laterally-curved track-plate mounted on the supporting means between the guides and bearing against the portions of the cables passing 110 thereover.

19. In an aerial tramway, the combination with spaced supports, of spaced plates mounted on each support, a guide-sheave journaled between the plates of each support, a track-cable passing over each sheave, and a curved track-section plate bridging the space between the supports, the ends of said plate being engaged between the spaced sets of plates on the support and being disposed in 120 coacting relation to the ends of the track-cable.

20. In an aerial tramway, the combination with spaced supports, of a track-section connected to each support and comprising a single 125

gle cable having spaced stretches, said stretches forming substantially parallel carriage-supporting rails, and curved track-plates bridging the space between the supports and between the corresponding cable-rails of each track-section, said track-plates having their ends aligned with the cable-rails.

In testimony that I claim the foregoing as my own I have hereto affixed my signature in the presence of two witnesses.

WILLIAM C. LAWSON.
